LOAD BINDER

George R. Juline, Warren, Pa., assignor to Warren
Axe and Tool Co., Warren, Pa., a corporation of
Delaware

Application February 8, 1933, Serial No. 655,741

4 Claims. (Cl. 24—68)

This invention relates to improvements in load binders or pulling implements which are employed to facilitate the fastening of loads with chains, cables and the like.

5 One of the objects of the invention is to provide an efficient tool of this character which is strong and durable in construction, and which is provided with yieldable means for automatically taking up any slack in the chain and for absorbing any shocks or strains transmitted to the tool or the load-engaging chain.

Another object of the invention is to so design and construct the tool that any kinks in the chain may be easily removed and further to so design 15 the tool that the same is positively prevented from being accidentally opened and releasing the load.

Other features of the invention reside in the construction and arrangement of parts herein-after described and particularly pointed out in 20 the appended claims.

In the accompanying drawing:—Figure 1 is a fragmentary perspective view showing the improved tool in use. Figure 2 is a side view of the tool showing the same in its open position. Figure 3 is a similar view of the tool in its closed position. Figure 4 is an elevation view of the tool looking at right angles to Figure 3. Figure 5 is an enlarged, fragmentary, vertical section taken substantially in the plane of line 5—5, Figure 3. 30 Figure 6 is an enlarged fragmentary vertical section taken on line 6—6, Figure 4.

Similar characters of reference indicate corresponding parts throughout the several views.

By way of example, I have shown my improved 35 tool in connection with the tying or binding of a load 10 to a truck-platform or the like, the ends of the tool being connected to the opposing ends of the chain 11 or like element encircling the load.

The improved tool consists of an actuating lever 40 12, one end of which is shaped to constitute a handle to operate the tool to bind or release the load, while the other end is bifurcated to provide spaced arms 13, this bifurcated portion being preferably deflected relative to the handle and bent or shaped substantially in the form of a V. 45 At their free ends these arms are provided with outwardly-extending pivots or trunnions 14 and pivotally connected to these trunnions is a clevis 15 which is free to embrace or straddle the V-shaped portion 13 of the lever in the closed or 50 clamped position shown in Figures 1 and 3, and which has a swiveled eye 16 mounted thereon to which a chain-engaging hook 17 is connected. The outer ends of the trunnions preferably terminate in elongated heads 18 and the free ends 55

of the clevis 15 are provided with similarly shaped openings 19 for permitting the ready assemblage of the clevis to the lever-trunnions. The trunnion-heads are so disposed that when the lever is clamped down to its load-tightening position, 60 as seen in Figures 1 and 3, these heads are out of register with the clevis-openings 19 so that there is no danger of the clevis springing out of engagement with the trunnions.

The means for connecting the other end of the 65 binding chain 11 to the tool consist of a swinging arm or tongue 20 pivoted at 21 to the apex of the V-shaped arm portion of the lever 12 so as to swing in the space between the bifurcated arms 13. At its outer or free end this tongue carries 70 a swiveled eye 22 and interposed between the latter and the hook 23 to which such other end of the chain is coupled is a yieldable connection or shock absorber which functions to automatically take up any slack in the chain should the 75 load settle as well as absorbing any shocks or strains to which the binder and load-engaging chain may be subjected. This connection preferably consists of a coil spring 24 to which are applied oppositely-facing loops 25, 26, the loop 80 25 being coupled to the swivel eye 22 and the companion loop 26 being joined to the hook 23. These loops extend through the opening in the coil spring and are disposed at right angles to each other, each terminating at their free ends 85 in reversely-bent hooks 27 embracing the opposite ends of the spring as seen in Figure 6, so that when a pull is exerted on the loops 25, 26 and connected parts the spring is compressed.

In using the tool, the chain 11 or other tying 90 element is wrapped about the load with the ends of the chain facing each other, say at the side of the load, as shown in Figure 1. The tool, while in its open position shown in Figure 2, is then interposed between the ends of the chain and its 95 hooks 17 and 23 are coupled thereto, after which the handle of the lever 12 is pulled downwardly, causing the clevis 15 and the tongue 20 to be brought toward each other to firmly and effectively tighten the chain about the load. When 100 moving the lever to its closed or clamped position, its V-shaped arm portion 13 passes through the clevis and the tongue 20 swings to a substantially upright position with the swivel eyes 16 and 22 in substantial alignment and the pivot 105 21 of the tongue 20 displaced somewhat beyond the lever-trunnions 14, whereby the lever is effectively locked in its closed or load-tying position. Furthermore, in this position the spring 24 is strained and under tension and posi- 110

tively tends to retain the lever 12 in its closed position, thereby eliminating accidental opening of the lever and the dispersement of the load. Should the load settle, this spring also comes into play in automatically taking up any slack in the chain to keep the load bound tight at all times and it performs the further function of a shock absorber in lessening to a material degree the strains imposed upon the chain and the binder tool. By the provision of the swivels 16 and 22, any kinks in the chain 11 may be easily removed from both ends without disturbing the position of the tool, and in addition to this advantage the swivels permit the tool to be tipped to one side or the other of the chain to lie flatwise against the load.

I claim as my invention:-

1. A load binder, comprising an actuating lever having a bifurcated portion, means pivoted to and embracing said bifurcated portion for connecting it to one end of a load-engaging chain and relative to which said lever is movable to a clamped or released position, a member pivotally disposed within the bifurcated portion of said lever for movement thereby toward and from said lever-means and having means at its free end for connecting it to the other end of the load-engaging chain, and a yieldable element interposed between said member and the opposing end of the chain and tending to resist movement of said lever out of its clamped position.

2. A load binder, comprising an actuating lever having a laterally off-set V-shaped bifurcated portion, a clevis pivotally connected to the exterior of the bifurcated portion of said lever and having means thereon for connecting it to one end of a load-engaging chain, an arm pivoted to the apex of the bifurcated portion of said lever at a point spaced from the clevis-pivot for connection to the opposite end of the chain, and a

shock-absorbing element interposed between said member and the companion end of the load-engaging chain.

3. A load binder, comprising an actuating lever shaped to form a handle at one end and terminating in a bifurcated portion at its other end having trunnions thereon, a clevis embracing the bifurcated portion of said handle and pivoted to said trunnions and adapted for connection to one end of a load-engaging chain, an arm pivoted within the bifurcated portion of said lever at a point above and laterally displaced from said trunnions and movable toward and from said clevis when the lever is swung to its closed and opened positions about the trunnions, and means for connecting said arm to the opposite end of the load-engaging chain, said means including a tension spring acting on a line intersecting the pivot connecting said arm with said lever and whereby said spring constantly resists movement of said lever out of its operative closed position.

4. A load binder, comprising an actuating lever having a laterally off-set, V-shaped bifurcated portion at one end, a clevis pivotally connected to the end of and embracing the bifurcated portion of said lever, an arm disposed between, and pivoted to said lever, adjacent the apex of its bifurcated portion, and movable therewith toward and from said clevis, swivel elements mounted on the free ends of said clevis and said arm and adapted for connection to the ends of the load-engaging chain, and a spring interposed between one of said swivel elements and the adjoining end of the chain for automatically taking up slack in the chain and for preventing movement of the lever out of its clamped position the line of pull of said spring being such as to resist movement of the lever out of such clamped position.
